UNITED STATES PATENT OFFICE

2,602,456

BOBBY PIN OPENER

Harold A. Le Master, Bradley, Ill.

Application September 7, 1950, Serial No. 183,502

1 Claim. (Cl. 132—1)

1

This invention relates to new and useful improvements and structural refinements in devices for opening bobby pins, and the principal object of the invention is to provide a device of the character herein described which, in the manner of a finger ring, may be applied to fingers of a user, so that it is efficiently sustained in an operative position while the fingers remain quite free for manipulating the hair.

Although I am aware that in the past bobby pin opening devices have been designed for positioning on a finger, such devices had the disadvantage that when a bobby pin was applied thereto for opening purposes, any pressure exerted on the pin caused the device to rotate about the finger, thus rendering the same ineffective. It is, therefore, a principal feature of the instant invention to provide a device which is adapted for positioning on two juxtaposed fingers, the finger receiving portion of the device being elongated, and, therefore, discouraging any tendency of the device to rotate.

Some of the advantages of the invention reside in its simplicity of construction, in its pleasing appearance, in its efficient operation, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention shown in position on two fingers of a hand,

Figure 2 is a longitudinal sectional view of the invention per se, taken substantially in the plane of the line 2—2 in Figure 1, and

Figure 3 is a transverse sectional view of the invention per se, taken substantially in the plane of the line 3—3 in Figure 1.

Like characters of reference are employed to designate like parts in the specification and throughout the several views.

Referring now to the accompanying drawings in detail, the invention consists of a bobby pin opener which is designated generally by the reference character 10 and embodies in its construction an elongated, substantially rectangular body 12 which is provided at the underside thereof with a longitudinally extending rigid band 14 defining an elongated endless opening or loop 16 which is adapted to receive two juxtaposed fingers 18, 20 of a hand, as shown in Figure 1.

The "height" of the opening 16 conforms sub-

stantially to the "thickness" of the fingers 18, 20 while the "length" of the opening conforms substantially to the combined "width" of the two fingers, whereby the entire device is prevented from rotating about the fingers when pressure is applied thereto by a bobby pin.

The body 12 has stepped marginal edge portions which afford a series of perimetric extending, horizontal ledges 22, 24, 26 and a series of perimetrically extending, undercut wall portions 28, 30, 32 which extend downwardly and inwardly from the respective ledges, as shown. The respective ledges coact with the respective undercut wall portions in defining a series of stepped, relatively sharp and perimetrically extending edges 34, 36 and 38, to which the legs of a conventional bobby pin 40 may be applied for spreading the same, as is shown in Figure 2.

Needless to say, any one of the perimetric edges 34, 36, 38 may be used for spreading the legs of the bobby pin, but when the bobby pin opening operation is undertaken, the legs of the pin are preferably applied to the lowermost edge 34 and upward pressure is exerted on the pin to open the same.

If it should occur that the legs of the bobby pin slip upwardly from the lowermost edge 34, such as by accident or mistake, the legs of the pin will automatically come in opening engagement with the intermediate edge 36 or with the uppermost edge 38, as the case may be.

It is believed that the advantages and use of the invention will be clearly understood from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

In a bobby pin opener, a substantially rectangular body having stepped marginal edge portions affording a series of perimetrically extending horizontal ledges and perimetrically extending undercut wall portions below the respective ledges, said wall portions having downwardly and inwardly sloping surfaces, said ledges and respective wall portions defining a series of stepped relatively sharp and perimetrically extending edges for spreading the legs of a bobby pin and

a rigid band provided on the underside of said body and defining an elongated endless loop adapted to receive two juxtaposed fingers of a hand, whereby to non-rotatably sustain the opener in position on the stated fingers.

HAROLD A. LE MASTER.
